(57) **CLAIM**

The ornamental design for vehicle mountable inverter, as shown and described.

DESCRIPTION

FIG. 1 is a top plan view of a vehicle mountable inverter, showing our new design;

FIG. 2 is a bottom view thereof;

FIG. 3 is a front elevational view thereof;

FIG. 4 is a rear elevational view thereof;

FIG. 5 is a left hand side elevational view thereof;

FIG. 6 is a right hand side elevational view thereof; and,

FIG. 7 is a perspective view thereof.

The broken line showing of a vehicle mountable inverter is for illustrative purposes only and forms no part of the claimed design.
